UNITED STATES PATENT OFFICE.

LEWIS GOODWIN, OF BOSTON, MASSACHUSETTS.

CORNER BRACE OR SUPPORT FOR PLASTERING.

SPECIFICATION forming part of Letters Patent No. 595,299, dated December 14, 1897.

Application filed May 22, 1896. Renewed August 5, 1897. Serial No. 647,244. (No model.)

To all whom it may concern:

Be it known that I, LEWIS GOODWIN, of Boston, in the county of Suffolk and State of Massachusetts, have invented a new and useful Improvement in Corner Braces or Supports for Plastering, which will, in connection with the accompanying drawings, be hereinafter fully described, and specifically defined in the appended claims.

10 In said drawings, Figure 1 shows my improved corner brace or support as when applied to support the corner-plastering of two intersecting walls, forming a reëntrant angle, and as secured to the studding of the wall 15 and extended outward therefrom through the lathing and having its outer angle-arms or branches embedded in the plastering. Fig. 2 is a similar view, but showing the metallic support as secured to the outer face of the 20 lathing and extended into the body of the plastering. Fig. 3 is a perspective view of a section of the metallic corner piece or strip as bent or folded into form for practical use. Fig. 4 is like Fig. 3, except a slight change in 25 form.

The object of my invention is to furnish, as illustrated in said drawings, a light metallic support for the plastering of rooms at the corners or reëntering angles of their intersecting walls, which, when properly secured to the lathing or studding and embedded in the wall-plaster, will hold the latter firmly in place and maintain an unbroken surface against any tendency to crack or separate at the reëntrant corners from shrinkage of the woodwork; and the invention consists in a support or brace A, composed of a thin piece or strip of flexible sheet metal, bent into the form shown, with broad wings 30 B B at right angles to each other, which are, when in practical use, attached at proper intervals, by nails or screws through their outer edges, to the woodwork behind the plastering, and with a folded straight arm C, extending outward from said woodwork midway between said wings and terminating in a right-angled fold, the branches D D of which are parallel with wings B B.

In the practical application of this corner-piece, which is especially designed for reëntrant angles or corners, as illustrated in Fig. 1, the wings B B are shown as attached to the studding E E by means of screws F F, said wings extending between the lathing G G and the studding, while the folded central 50 arm C reaches outward through the lathing, and its angular termination is embedded in the body of the plastering H, the greater portion of which in the corner is clenched by the branches D D, and thereby held from drawing away from the woodwork or separating at the junction of the two wall-surfaces.

In the practical application of the folded strip or piece of metal, as illustrated in Fig. 2, the wings are similarly attached, but have 65 their bearing against the outer face of the lathing instead of between the latter and the studding, as in Fig. 1, and the attaching-screws extend through both the wing and lathing. The parts embedded in the plastering 70 are substantially the same in the two figures.

In certain classes of plastering one of the wings of the brace may be omitted for convenience in using the invention without essentially departing therefrom, leaving it as shown in Fig. 4.

I claim—

1. A metallic corner support or brace, composed of a strip or piece of thin, flexible metal, 80 bent and folded into form to adapt it to support the plastering of reëntrant angles or corners and comprising wings B B; arm C; and branches D D, arranged substantially as described, and for the purpose specified. 85

2. A metallic corner-support, composed of a strip of flexible metal, bent and folded into form so as to comprise an attaching-wing B; an arm C; and branches D D: all arranged and adapted to support the plastering of re- 90 ent angles or corners, substantially as shown and described.

LEWIS GOODWIN.
